PAPER MACHINE DRIVE

Milton T. Weston, Red Bank, N. J., assignor to
 West Virginia Pulp & Paper Company, New
 York, N. Y., a corporation of Delaware

Application January 7, 1938, Serial No. 183,745

8 Claims. (Cl. 34—48)

My present invention relates to improvements in drives for paper making machines, and more particularly for the individual cylinders of the drier section. The present practice is to positively gear all of the drier cylinders in the section together so that the peripheries of all of the cylinders have exactly the same velocity. On account of the snubbing action of so many cylinders, and further because the tension in the felts holds the paper web firmly against the surfaces of the drier cylinders, there can be no slipping of the paper web to allow for the normal shrinkage which, in a modern machine, is very considerable—probably as much as ten to twenty feet between the first and last drier cylinder. The effect is, in reality, the stretching of the paper web to this extent in the machine direction, causing an abnormal shrinkage in the cross direction. This stretching of the paper results in a pronounced orientation of the fibers in the machine direction at the expense of the cross direction, making the paper much stronger in the one direction than in the other. Repeated tests have shown that the prevention of the normal shrinkage of the paper web produces a sheet 2½ times stronger in the machine direction than in the cross direction—a very undesirable result. Other tests have proven that most of the fiber orientation in the present system occurs at the drier section. If this orientation of the fibers in the machine direction can be prevented by allowing the paper web to shrink normally, a condition will result wherein the paper web will be more nearly equal in strength in both directions—a most desirable result.

The principal object of my invention is to provide a drive mechanism for the drier unit in which the individual cylinders of the unit may be driven at speeds which differ by extremely slight increments from one another, thereby making it possible to obtain the required fineness of adjustment necessary for a progressive difference in peripheral speeds of the several drier cylinders from the first to the last to allow for the proper shrinkage of the paper web and thus prevent orientation of the fibers in the machine direction.

A further object is to provide an improved drive arrangement for the drier units in which my improved micro variable drive is applied to a selected group of cylinders.

A further object is to provide an improved mechanism employing a planetary gear train and means for driving same in which variation in drive of the unit as a whole will not affect the

relative speeds of the individual cylinders one to another.

A further object is to provide an improved means of disposition of the planetary gear motors.

Further objects of the invention and advantages will be apparent from the following detailed description taken with the accompanying drawings in which

Fig. 1 is a side elevation of an illustrative embodiment, a part being shown in cross section taken on line 1—1 of Fig. 3.

Fig. 2 is a cross sectional view taken on a line 2—2 of Figs. 3 and 4 showing the supports for the control motors.

Fig. 3 is a cross sectional view of a unit of my invention on a line 3—3 of Fig. 1.

Fig. 4 is a cross sectional view similar to Fig. 3 showing a different form of the same mechanism.

Fig. 5 is a side elevation showing several units of my invention in operative relation to each other and reveals the means for supporting all of the control motors independent of the paper machine.

Fig. 6 is a diagrammatic view illustrating the use of a so called "silent" driving chain instead of the train of meshing gears.

Fig. 7 shows a circuit which may be employed for connecting up the auxiliary motors.

Fig. 8 is a diagrammatic view of the drier cylinders in which my improved micro variable drive is applied to a selected group of cylinders; and

Fig. 9 represents a curve indicating a shrinkage of the paper as it passes through the rolls, and is so related to Fig. 8 that a vertical line drawn upwardly from any cylinder of Fig. 8 intersects the curve at the point indicating approximately the amount of shrinkage of the paper at that particular cylinder.

In the drawings, 1 is the trunnion on which a drier cylinder 2 is revolvably mounted. A spider 3 is keyed on the end of the trunnion 1 and is provided at its periphery with an integral radial flange 4 and a preferably removable radial flange 5. A gear ring 6 is revolvably mounted on the peripheries of radial flanges 4 and 5 as clearly shown in Figs. 1 and 3. The outer periphery of the gear ring 6 is provided with spur teeth to mesh with similar teeth on gear rings 6 carried by adjacent units as shown in Fig. 5. The inner periphery of the gear ring 6 has internal spur teeth 7 which are disposed in the annular space 8 between the flanges 4 and 5 as

50

55

shown at the bottom of Fig. 3 and in the broken section in Fig. 1.

The rim of the spider 3 has a plurality of transverse pockets or recesses 9 in which are located 5 spur pinions 10 with integral shafts 11 revolvably mounted in flanges 4 and 5 in proper relation to mesh with the internal teeth 7 on the gear ring 6. Obviously, turning the pinions 10 about their axes will cause a rotational movement of the gear 10 ring 6 with respect to the flanges 4 and 5 and consequently with respect to the spider 3.

On the outer ends of the pinion shafts 11 are mounted worm wheels 12 meshing with worms 13 operably mounted on shafts 14 which extend 15 somewhat radially toward the axial center of the unit. The inner ends of these shafts 14 are supported in a casing 15 attached to the hub of the spider 3. Bevel pinions 16 are mounted on the inner ends of shafts 14 within the casing 15 and mesh with a bevel gear 17 mounted on a sleeve 18 revolvable on the steam inlet pipe 19 secured to and revolving with the trunnion 1. A wormwheel 20 is mounted on the outer end of the sleeve 18 and is driven by a worm 21 mounted 25 in operable position in the casing 22 which preferably is suspended from the sleeve 18 by its own bearings 23 on either side of the worm wheel 20. A fin 24 projects downwardly from the casing 22 and supports the angles 25, which are securely 30 attached to it in a horizontal position, and which support the control motors 26 in axial alignment with the worm 21 in casing 22. By reference to Fig. 5 it will be seen that these angles 25 extend continuously past all of the units of the drier 35 section of a paper machine and support all of the control motors 26. This construction entirely avoids any attachment to the paper machine for supporting the control motors and also makes cumbersome and obstructing supports on the floor unnecessary.

The customary arrangement for admitting steam to a drier cylinder and removing condensate therefrom is illustrated by the parts A and B, respectively, in Figs. 3 and 4.

Fig. 4 shows the embodiment of my invention 45 in a more compact form. Instead of the gear ring 6 I use a complete gear 27 having a hub 28 which is somewhat larger in diameter than usual in order to accommodate the internal teeth 29 50 and permit the mounting of the pinions 10 in proper positions to mesh with the internal teeth. This also brings the worm wheels 12 and worms 13 toward the axial center as far as structurally possible. The hub 28 is revolvably mounted on 55 flange 30 keyed on trunnion 1 and on the removable flange 31 and the pinion shafts 11 are also revolvably mounted in these flanges.

In this same figure I show another modification in construction wherein I provide a sleeve 60 32 integral with or attached to the removable flange 31 and concentric with the steam inlet pipe 19 but not in contact with it. This permits the ready removal of the steam inlet pipe 19 without disturbing the unit. The worm wheel 65 33 is revolvably on the sleeve 32 and has its hub extended to receive the bevel gear 34 secured thereon. The control motor mounting is the same as described for Fig. 3.

For an understanding of the operation of the 70 device of Figs. 1-3, assume that it is desired to drive the cylinder 2 at the same speed (R. P. M.) as the gear 6. To accomplish this it is evident that the spur pinions (planets) 10 should remain fixed upon their axes. For this condition to occur the bevel gear 17 must remain fixed in

relation to the spur gears 16 and hence gear 17 must be driven at the same speed (R. P. M.) as gear 6. If, however, the auxiliary motor is driven at a somewhat faster speed the arrangement is such that the pinions 11 will be rotated slightly 5 in the same direction as the inner gear 7 and hence will cause a corresponding diminution of speed of the flange 5, spider 3 and cylinder 2. The operation of Fig. 4 is precisely similar.

Fig. 6 shows the use of the "silent" type of 10 sprocket chain 35 in which alternate links are reversed in order to operate on sprocket wheels 36 which are alternately presented on both sides of the chain 35 as illustrated in this figure. It will be understood that sprocket teeth are provided in place of the meshing gear teeth previously described.

In the operation of my invention all or a portion of the drier cylinders are progressively slowed down as the paper web advances. The 20 reduction in the peripheral speed of the successive cylinders represents the exact amount of shrinkage in the paper web, so that shrinkage will take place substantially equally in both directions resulting in the paper having approximately equal strength in the machine and cross 25 directions. The adjustment and regulation of the speeds of the several cylinders in my invention is accomplished by varying the speeds of the several control or auxiliary motors 26—one 30 motor being provided for each drier unit as shown in Fig. 5. The control motor 26, operating through the gearing as described, slows down its corresponding drier cylinder in proportion to its speed. That is, the faster the motor 35 speed the slower the speed of the corresponding drier cylinder. Each successive control motor will therefore run slightly faster than the preceding one and these speeds are determined and regulated to slow down the drier cylinders 40 progressively to allow for the normal shrinkage of the paper web.

In Fig. 7 I have shown a circuit which may be employed for connecting up the auxiliary motors 45 50 by means of which the speed of the drier unit may be varied as a whole without altering the relative speed of the individual cylinders. As shown, a source of D. C. power 50 is employed of constant electromotive force (E. M. F.). Source 50 is connected to a motor 51 driving a D. C. generator 52, means being provided for varying the speed of motor 51 in the form of rheostat 53. The circuit 54, energized by generator 52, is now employed for driving the main motor 54a for the drier unit, the same driving the gear train comprised of the intermeshing annular gears 6 by a pinion 54b through the branch circuit 55, while branch circuit 56 is employed to drive the armatures 57 of motors 26. The fields for the motors 26 are indicated at 59. It will be apparent thus far that the flux afforded by fields 59 remaining constant, the speed of motors 26 will vary automatically with that of the main motor 54a connected with branch circuit 55. It is desirable, however, to vary the speed of the motors 26 by slight increments with respect to one another, and for this purpose circuit 60 is provided, also energized by generator 50 and therefore having a constant E. M. F., such circuit feeding the field circuits 61 as shown. It is now merely necessary 70 in such circuits 61 to provide rheostats 62 by means of which to alter the flux of the fields 59, and hence provide means for varying the speed of the motors 26 with respect to one another. It will therefore be seen that by adjusting the 75

5 rheostat 53, the speed of the main motor 54a and of the auxiliary motors will be varied as a unit, whereas adjustment of the individual rheostat 62 will vary the speed of the individual cylinders with respect to one another.

10 I have also discovered that the shrinkage of the paper is not uniform as the paper passes from drying cylinder to drying cylinder, but instead, is represented by a curve having a form as shown by Fig. 9. Reference to this curve will bring out the fact that as the web comes from the presses containing, say, about 66% moisture, it does not undergo any appreciable shrinkage for perhaps one-third of the entire drier section 15 represented by A, Fig. 8, the heat of the cylinders going to heat up the relatively cold, wet paper. However, beginning at period B the continued gradual heating of the web results in evaporation of the moisture, at which time shrinkage takes 20 place. The rate of shrinkage at this point is substantially uniform until approximately another third of the drier units have been traversed. Beginning at section C, however, the shrinkage again falls off because of the lowered rate of 25 evaporation, and the curve becomes substantially flat, as indicated in Fig. 9.

30 In my present invention I take advantage of this difference in the rate of shrinkage by driving the cylinders of section A together at a uniform rate one with respect to the other. However, in section B wherein the greater shrinkage takes place, I provide for individual cylinders having a differential drive with respect to one to the other, employing the means for this previously described. After section B is traversed the cylinders comprising group C are driven again at uniform rate relative one to another, except, however, the unit as a whole is driven at a speed which is proportionately slower than the speed 40 of the A units. This result may be brought about by increasing the size of the gears in group C, thus causing the cylinders driven thereby to run proportionately slower and at exactly the same speed as that of the last cylinder in group 45 B and preventing any strain in the paper as it passes from group B to group C. In Fig. 9, 65 represents the slight amount of shrinkage the paper has undergone at the start of the group B, while 67 indicates the amount of shrinkage 50 occurring in group C, the bulk of the shrinkage occurring in group B being represented by 66. While the amount of shrinkage represented by 67 is slightly greater than that represented by 65, this does not injure the paper, since the web is 55 substantially formed by the time it reaches group C and will have sufficient elasticity and slip to take care of this remaining shrinkage without injury.

60 The arrangement just described effects a substantial economy of installation and in most cases sacrifices no substantial benefit of the invention. However, in special cases, especially where the shrinkage characteristics of the paper differ from the normal, for the best results group 65 C driers may be eliminated and group B made large enough to complete the drying. In such a case the saving in installation will be represented by that of group A.

70 I wish it understood that various changes will occur to those skilled in the art from the specific embodiments shown, which are illustrative only, without departing from the spirit of my invention or the scope of the appended claims. This application is a continuation in part of my application Serial No. 96,805 filed August 13, 1936.

I claim:

1. In a paper making machine, a group of drier cylinders, supporting shafts or trunnions for said cylinders, means for driving said cylinders including drive receiving members respectively associated with said cylinders and operatively connected thereto, driving gears concentric with respective of said drive receiving members, said driving gears meshing with one another to constitute a gear train in which each driving gear has approximately the same speed of rotation, differential gear connections between corresponding of said driving gears and said drive receiving members, and means for actuating said connections to vary the speed of the individual drier cylinders of the group in an amount to compensate for the shrinkage of paper from one drier cylinder to another. 5

10 2. In a paper making machine, a group of drier cylinders, supporting shafts or trunnions for said cylinders, means for driving said cylinders including drive receiving members respectively associated with said cylinders and operatively connected thereto, driving gears concentric with respective of said drive receiving members, 20 said driving gears meshing with one another to constitute a gear train in which each driving gear has approximately the same speed of rotation, differential gear connections between corresponding of said driving gears and said drive receiving members, and means for actuating said connections to vary the speed of the individual drier cylinders of the group in an amount to compensate for the shrinkage of paper from one drier cylinder to another, said actuating means 30 comprising an electric motor individual to each of said differentially driven cylinders and supporting means for each of said motors suspended from a plurality of said shafts or trunnions. 35

40 3. In a paper making machine, a group of drier cylinders, supporting shafts or trunnions for said cylinders, means for driving said cylinders including drive receiving members respectively associated with said cylinders and operatively connected thereto, driving gears concentric with respective of said drive receiving members, said driving gears meshing with one another to constitute a gear train in which each driving gear has approximately the same speed of rotation, differential gear connections between 45 corresponding of said driving gears and said drive receiving members, and means for actuating said connections to vary the speed of the individual drier cylinders of the group in an amount to compensate for the shrinkage of paper from one drier cylinder to another, said actuating means 50 comprising an electric motor individual to each of said differentially driven cylinders and supporting means for each of said motors comprising a bar upon which said motors are attached, and sleeves on a plurality of said shafts or trunnions and supporting said bar. 55

60 4. In a paper making machine, a group of drier cylinders, supporting shafts or trunnions for said cylinders, means for driving said cylinders including drive receiving members respectively associated with said cylinders and operatively connected thereto, driving gears associated with respective of said drive receiving members, 65 said driving gears meshing with one another to constitute a gear train in which each driving gear has approximately the same speed of rotation, differential gear connections between corresponding of said driving gears and said drive receiving members, a main electric motor for 70

- driving said drier cylinders through said gear train, means for actuating said connections to vary the speed of the individual drier cylinders of the group comprising auxiliary electric motors, one for each connection, electric connections between said main motor and said auxiliary motors including means for varying the speed of said auxiliary motors in accordance with said main motor, and means for changing the speed of said auxiliary motors independently of said main motor.
5. In a paper making machine, a group of drier cylinders, supporting shafts or trunnions for said cylinders, means for driving said cylinders including drive receiving members respectively associated with said cylinders and operatively connected thereto, annular driving gears having gear teeth on both their inner and outer surfaces and being concentric with respective of 10 said drive receiving members, said driving gears meshing with one another to constitute a gear train in which each driving gear has substantially the same speed of rotation, planetary gears between corresponding of said driving gears and 15 said drive receiving members, means for driving said planetary gears to vary the speed of the individual drier cylinders of the group in an amount to compensate for the shrinkage of paper from one drier cylinder to another.
- 20 6. In a paper making machine, a group of drier cylinders, supporting shafts or trunnions for said cylinders, means for driving said cylinders including drive receiving members respectively associated with said cylinders and operatively connected thereto, annular driving gears having gear teeth on both their inner and outer surfaces and being concentric with respective of 25 said drive receiving members, said driving gears meshing with one another to constitute a gear train in which each driving gear has substantially the same speed of rotation, planetary gears between corresponding of said driving gears and said drive receiving members, means for driving 30 said planetary gears to vary the speed of the individual drier cylinders of the group in an amount to compensate for the shrinkage of paper from one drier cylinder to another.
- 35 7. In a paper making machine, a group of drier cylinders, supporting shafts or trunnions for said cylinders, means for driving said cylinders including drive receiving members respectively associated with said cylinders and operatively connected thereto, annular driving gears having gear teeth on both their inner and outer surfaces and being concentric with respective of 40 said drive receiving members, said driving gears meshing with one another to constitute a gear train in which each driving gear has substantially the same speed of rotation, planetary gears between corresponding of said driving gears and said drive receiving members, means for driving said planetary gears to vary the speed of the individual drier cylinders of the group in an amount to compensate for the shrinkage of paper from one drier cylinder to another.
- 45

per from one drier cylinder to another, said means last mentioned comprising a rotatable sleeve concentric with each supporting shaft or trunnion, said sleeves accommodating steam inlet pipes for heating said cylinders.

5 8. In a paper making machine, a group of drier cylinders, supporting shafts or trunnions for said cylinders, means for driving said cylinders including drive receiving members respectively associated with said cylinders and operatively connected thereto, driving gears concentric with respective of said drive receiving members, said driving gears meshing with one another to constitute a gear train in which each driving gear has approximately the same speed of rotation, a main electric motor for driving said cylinder through said gear train, differential gear connections between corresponding of said driving gears and said drive receiving members, and means for actuating said connections to vary the speed of the individual drier cylinders of the group in an amount to compensate for the shrinkage of paper from one drier cylinder to another, said actuating means including an auxiliary electric motor in circuit with said main motor whereby said auxiliary motor keeps pace with said main motor, and a speed adjusting device associated with said auxiliary motor to vary the speed of same independently of said main motor.

10 9. In a paper making machine, a micro drive for individual cylinders of the drier section, comprising a driving member in the form of an annular gear having gear teeth both on its inner and outer surfaces, the outer teeth of said gear adapted to mesh with the outer teeth of like gears in a nest of driers, and to be driven at a relatively constant peripheral speed, driving means for same, a drive receiving member connected to a drier cylinder and co-axial therewith, planetary gears adapted to mesh with said teeth on the inner surface of said annular gear and with teeth on said drive receiving members and means for driving said planetary gears at a variable speed to vary the speed of said drier cylinder.

15 20 25 30 35 40 45 MILTON T. WESTON.
